(57) **CLAIM**

The ornamental design for an electrical stimulation device, as shown and described.

DESCRIPTION

FIG. 1 is a perspective view of an electrical stimulation device embodying our new design;

FIG. 2 is another perspective view thereof;

FIG. 3 is another perspective view thereof;

FIG. 4 is front view thereof;

FIG. 5 is rear view thereof;

FIG. 6 is a left side view thereof;

FIG. 7 is a right side view thereof;

FIG. 8 is a top view thereof; and,

FIG. 9 is a bottom view thereof.

Broken lines, where shown, are used to illustrate portions of the electrical stimulation device that form no part of the claimed design.
